UNITED STATES PATENT OFFICE.

GUSTAF J. KALLANDER, OF SEATTLE, WASHINGTON.

DESIGN FOR A TEETERING TOY.

59,356.

Specification for Design.

Patented Oct. 11, 1921.

Application filed June 9, 1921. Serial No. 476,358. Term of patent 7 years.

To all whom it may concern:

Be it known that I, GUSTAF J. KALLANDER, a citizen of the United States, residing at Seattle, in the county of King, State of Washington, have invented a new, original, and ornamental Design for a Teetering Toy, of which the following is a specification, reference being had to the accompanying drawing, forming part thereof.

This figure is a perspective view of a teetering toy constructed according to the present invention.

I claim:

The ornamental design for a teetering toy as shown.

GUSTAF J. KALLANDER.
